(57) **CLAIM**

The ornamental design for a face mask cushion and frame assembly, as shown and described.

DESCRIPTION

FIG. 1 is a top, front and side perspective view of a face mask cushion and frame assembly embodying our new design;

FIG. 2 is a top, rear and side perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

Broken lines are used to illustrate portions of the face mask cushion and frame assembly which form no part of the claimed design.

1 Claim, 8 Drawing Sheets
